UNITED STATES PATENT OFFICE.

LEWIS M. ELWELL, OF ZANESVILLE, OHIO.

DESIGN FOR A MONUMENT.

42,664.

Specification for Design.

Patented June 25, 1912.

Application filed May 3, 1912. Serial No. 694,967. Term of patent 7 years.

To all whom it may concern:

Be it known that I, LEWIS M. ELWELL, a citizen of the United States, residing at Zanesville, in the county of Muskingum, State of Ohio, have invented a new, original, and ornamental Design for Monuments, of which the following is a specification, reference being had to the accompanying drawing, forming part thereof.

The figure is a perspective view of a monument, showing my new design.

I claim:

The ornamental design for a monument, as shown.

LEWIS M. ELWELL.

Witnesses:

GEORGIA BAIRD,

GRACE DEMNEY.
